UNITED STATES PATENT OFFICE.

GIULIO MARCHETTI, OF HALIFAX, ENGLAND.

DESIGN FOR CARPET.

SPECIFICATION forming part of Design No. 23,407, dated July 3, 1894.

Application filed April 17, 1894. Serial No. 507,927. Term of patent 3½ years.

To all whom it may concern:

Be it known that I, GIULIO MARCHETTI, a subject of the Queen of Great Britain, and a resident of Halifax, in the Kingdom of England, have invented a certain new and original Design for Carpets and Borders, of which the following is a specification.

The accompanying drawing is a face view of a portion of a carpet and border embodying my invention.

My design consists of the body A and the border B.

The body A comprises a series of diamond shaped figures outlined by continuous wavy stemwork bearing small flower and leaf forms. Within each diamond shaped figure and following its outline is a serrated stem work and at the center of the figure are sprays of flower forms surrounded by one or more wreaths of small flower forms.

The border B comprises an inner and an outer portion. The inner portion consists of a continuous line of flowery stem work and a similar continuous wavy line bearing leaf like serrations. In the hollow of these wave portions are bunches or sprays of flower forms surrounded by serrated lines forming diamond shaped figures which are joined by a wavy stem work of flower forms. The hollows of this wavy stem work bear sprays of

flower forms surrounded by one or more circles of ornamental lines and flower forms. The outer portion of the border consists of a wavy stem work bearing small leaf and flower forms, the crests of the wave portions being joined by bands of flowery stem work, each of which is curved so as to form with its corresponding wave portion a circular figure. In the center of these circular figures is set a bunch or spray of small flower forms surrounded by an ornamental stem work. Between the oppositely curved outer sides of the contiguous figures are arranged spreading flower forms.

What I claim as my design, and desire to secure by Letters Patent, is—

1. In a design for a carpet, the body substantially as shown and described.
2. In a design for a carpet, the border substantially as shown and described.
3. The design for a carpet, comprising the body A and the border B substantially as shown and described.

In testimony whereof I have signed my name to this specification in the presence of two subscribing witnesses.

GIULIO MARCHETTI.
